UNITED STATES PATENT OFFICE.

ARTHUR A. BUCK, OF SCHENECTADY, NEW YORK, ASSIGNOR TO GENERAL ELECTRIC COMPANY, A CORPORATION OF NEW YORK.

OPERATING BULKHEAD-DOORS.

No. 853,765.

Specification of Letters Patent.

Patented May 14, 1907.

Application filed May 20, 1904. Serial No. 208,892.

To all whom it may concern:

Be it known that I, ARTHUR A. BUCK, a citizen of the United States, residing at Schenectady, county of Schenectady, State 5 of New York, have invented certain new and useful Improvements in Operating Bulkhead-Doors, of which the following is a specification.

My invention relates to control systems for water-tight bulk-head doors, and is adapted particularly for use on ship-board; although it is not limited to this particular application, but is also adapted to the control of fire hatches, doors, gates, valves, etc., in factories, theaters, etc.

In a control system for bulk-head doors, it is essential that all doors should be simultaneously controllable from a single point, and also that each individual door should be controllable locally, independently of the distant control, and irrespective of the condition at any instant of the distant control system. Thus, hydraulic systems have been devised, comprising hydraulically operated means at each door for closing it, all of said means being controllable from a single distant point, together with a manually controlled valve at each door adapted to disable the distant control and enable an operator at the door to 25 open or close it at will and regardless of the operation of the other doors by the distant control. Similarly, electrical systems have been devised, in which an electric motor is placed at each door and arranged, when energized, to open and close it, with a control system for all the motors enabling them to be simultaneously energized from a distant point, and a switch at each door for disabling the distant control by breaking the control 30 circuit and enabling the operator at the door to start the motor in either direction to open or close it, regardless of the operation of the other motors.

By my invention I do not at any time disable the distant control nor in any way modify the distant control system in order to obtain the requisite local control, but I provide elastic or yielding connections between the switch at the door and the distant controlling 45 means, so that the elastic connections may be strained to move the switch manually to any desired position, regardless of whether the distant control mechanism is energized or

not: that is, I provide a switch, yielding means for maintaining it normally in its off position, and a distant control system for shifting the point to which the switch tends to return when manually released, without in any way interfering with the manual control of the switch by straining the yielding returning means. When the manual operating means is released, the switch returns automatically either to its "off" position or to the position to which the distant control mechanism when energized tends to move it, 60 according as the distant control mechanism is deenergized or energized. The effect of the manually operated control upon the switch with reference to the distant control is simply that of straining the yielding connections between the switch and the distant control, while the effect of the distant control on the switch with reference to the manual control is simply that of shifting the position to which the switch returns when released. 75

My invention will best be understood by reference to the accompanying drawings, in which,

Figure 1 shows an electrically-operated bulk-head door, to which my invention is applicable; Fig. 2 shows a side elevation of the same, a cross-section being shown on the broken line *a a* of Fig. 1; Fig. 3 shows a perspective view of controlling switch arranged in accordance with my invention; Figs. 4 80 and 5 show modifications of the connections between the switch and the distant control mechanism; and Fig. 6 shows diagrammatically the arrangement of the control circuit.

In Fig. 1, *A* represents a bulk-head door 90 movable in the guides *A'*, and carrying the toothed rack *a'*. *B* is an electric motor driving the worm wheel *b*, which engages gear wheel *c* on shaft *C*. Shaft *C* also carries the pinion *c'*, which engages the toothed rack *a'*. 95 Thus, as the motor revolves in one direction or the other, the door *A* is raised or lowered. *D* represents a controlling switch which, in Figs. 1 and 2, is shown only in outline. Controlling switch *D* carries on its shaft the bevel gear *d*, which is engaged by the bevel gear *e* on shaft *E*, which carries the wheels or handles *e'* by means of which the controller 100 may be moved manually to its different positions.

In Fig. 3, *D* represents the motor control-

ling switch having the stationary contact fingers i , i' , etc., and two sets of movable contacts j to j' and k to k' , the former only being shown in this figure. Controlling switch D carries at one end the pin g , which is engaged by a spring h coiled around the shaft H, which is on a line with the shaft of controller D. The other end of spring h engages the pin g' , which is carried by one arm 5 of the bell-crank lever G rigidly secured to shaft H. The other end of bell-crank lever G is held against the stop s by the tension spring S, and is also connected to the core l of solenoid L. Spring h is so constructed 10 that its ends press toward each other, normally holding pins g and g' close together, as shown. Spring S acts to hold the bell-crank lever G, and consequently controller D in the position shown, which is the off-position of 15 the controller. Solenoid L is included in the distant control circuit, as will be hereinafter described. It is evident that if solenoid L is energized, core l will be drawn down, stretching tension spring S, rocking bell-crank lever 20 G, and rotating the cylinder D which, if free to revolve, will be driven by the spring h , pressing upon the pin g . The controller D may thus be moved to bring the movable contacts j , j' , etc., into engagement with the 25 stationary contacts i , i' , etc., thereby closing the motor circuit so as to close the door. If, however, it is desired to control the door locally, controller D may be rotated by means 30 of the wheels e' (shown in Figs. 1 and 2), against the tension of spring h , so as to move the controller to its off-position, or to the position for raising the door. Thus, by means of a yielding or elastic connection formed by the spring h , the door may be locally controlled at will, without interrupting 35 or altering in any way, the control circuit; but simply by manually over-powering the effect upon the control mechanism of the distant control system. When handle e' is released, however, the switch will return to the off-position as shown, if solenoid L is de- 40 energized but if solenoid L is energized the switch will return to the position in which contacts j , j' , etc. are in engagement with contacts i , i' , etc. Thus by moving the 45 handle, the effect of the solenoid may be over-powered and the switch moved to any desired position, while by the energizing of the solenoid the position to which the switch 50 tends to return when manually released is shifted.

In Fig. 4 another arrangement is shown in which the core l is rigidly connected to switch D, the normal off position being determined by the centering springs S and S'. With this arrangement it is necessary to pull core L out of the solenoid when it is desired to over-power manually the effect of the solenoid on the switch.

65 In Fig. 5, the centering spring S' is placed

above the core and the stop l' is provided for limiting the upward movement of the core and forming the abutment for the lower end of spring S' when switch D is in its normal off position. With this arrangement, as with that of Fig. 3, it is not necessary to pull core l out of the solenoid in order to over-power manually the effect of the solenoid on the switch. In all these arrangements and in many equivalent arrangements that may be devised, the solenoid shifts the position to which the switch tends to return when manually released.

Referring now to Fig. 6, m m' represent the mains or line-wires connected to any suitable source of current indicated by M. B and B' represent two operating motors for two doors. L represents the windings of the solenoid L of Fig. 3. The controlling switch D is shown with its contacts developed on a plane surface. N represents the distant control station comprising a plurality of switches n. The operation is as follows: Assume that the doors are raised, and that it is desired at station N to close all the doors on the ship. The switches n are thrown, and a circuit is closed from the mains m m' through solenoids L, L'. As has already been explained, the energizing of the solenoid rotates switch D, so as to bring the contacts 95 j , j' , etc., into engagement with stationary contacts i , i' , etc. The circuit is then completed, as follows: from main m to contact i , contact j , contact i' , through armature of motor B, contact i^2 , contact j^1 , contact i^3 , through field of motor B, contact i^4 , contact j^2 , contact i^5 , to main m' . The circuit of the motor is consequently closed, and the motor revolves in the proper direction to lower the door. Now if, while the door is closing, it is 100 desired by someone at the door to prevent its closing or to raise the door, the switch D may be drawn over to its off position or to its other running position, thereby bringing the contacts k , k' , into engagement with the stationary contacts i , i' , etc. It will be seen by tracing out the circuits that the motor B is again energized but with its armature reversed, and consequently will operate to 105 open the door.

It will be evident that the arrangement which I have shown and described may be greatly varied in many ways. The construction and arrangement of contacts of switch D, the means for holding it normally in off position, the connections between the distant control mechanism and the switch and the arrangement of circuits, may all be altered to meet varying requirements. Accordingly I aim in the appended claims to cover all such 120 modifications which do not depart from the spirit and scope of my invention.

What I claim as new and desire to secure by Letters Patent of the United States, is,

1. In combination, a device to be moved,

an electric motor for operating said device, a controlling switch for said motor, electro-responsive means controllable from a distance and adapted to operate said switch, elastic connections between said switch and said means, and manually operated means near said device for moving said switch independently of said electro-responsive means.

2. In combination, a device to be moved, a motor for operating said device, a controller for said motor, means for operating said controller from a distance, elastic connections between said controller and said operating means, and manually controlled means near said device adapted to move said controller independently of said operating means.

3. In combination, a device to be moved, an electric motor adapted to operate said device, a controlling switch for said motor, a solenoid having its core operatively connected to said switch and adapted when energized to move said switch to one of its running positions, and means for moving said switch to another position without disturbing the circuit of said solenoid or moving its core.

4. In combination, a device to be moved, an electric motor adapted to operate said device, a controlling switch for said motor, a solenoid adapted when energized to move said switch to one of its running positions, elastic connections between said switch and said solenoid, and means for manually straining said elastic connections so as to move said switch to another position without disturbing said solenoid.

5. In combination, a device to be moved, a motor for operating said device, a controller for said motor, means for operating said controller from a distance, elastic connections between said controller and said operating means, and means near said device for straining said elastic connections so as to move said controller without disturbing said operating means.

6. In combination, a system of doors, a motor for operating each door, a controller for each motor, a control system comprising a distant station and operating means for the several controllers controlled from the distant station, and an elastic connection between each controller and its operating means, whereby each controller may be moved by straining said elastic connection without moving the operating means.

7. In combination, a system of doors, an electric motor for operating each door, a controlling switch for each motor, a control system comprising electro-responsive operating means for the several controlling switches, control wires extending to a distant station and switches at said distant station, and an elastic connection between each controlling switch and its operating means, whereby each controlling switch may be moved by

straining the said elastic connection without moving the operating means or disturbing the connections of the control system.

8. In combination with an electric motor, a manually-operated reversing switch for said motor, means for maintaining said switch normally in its off position, and means controllable from a distant point for moving said maintaining means into a position to bring the said switch into one of its operative positions.

9. In combination with an electric motor, a manually-operated reversing switch for said motor, means for maintaining said switch normally in its off position, an electromagnet for moving said maintaining means into a position to close said switch, and means located at a distant point for controlling the circuit of said electromagnet.

10. In combination with an electric motor, a manually-operated reversing switch for said motor, maintaining means constructed and arranged to maintain said switch normally in its off position but to permit a free movement of the said switch through its manually-operated means, means for moving said maintaining means into a position to close the switch, and means located at a distant point for controlling the operation of the latter means.

11. In combination, a reversible motor, a manually-operated controlling device for causing said motor to operate in either direction, means for maintaining said controlling device normally in its off position, the said means being constructed and arranged to oppose the free movement of the said controlling device when it is manually operated and to return the said controlling device to a certain definite position when the manually-operated means is released, and means controllable from a distant point for moving said maintaining means into a position to cause the said controlling device to assume one of its operative positions.

12. In combination, an electric motor, a reversing switch for said motor, an operating handle for said switch, a switch moving member adapted to be actuated from a distant point to move said switch from its off position to one of its operative positions, and yielding means normally maintaining said reversing switch in a fixed position with reference to said switch moving member.

13. In combination, an electric motor, a reversing switch for said motor, an operating handle for said switch, a switch moving member arranged to maintain said switch normally in its off position and adapted to be actuated from a distant point to move said switch from its off position into one of its operative positions, and yielding means normally maintaining said reversing switch in a fixed position with reference to said switch moving member.

14. In combination, a manually-operated switch having a plurality of operative positions, means for maintaining said switch normally in its off position, and means controllable from a distance and adapted to shift the position to which said switch is returned when manually released.
15. In combination, a manually-operated switch having a plurality of operative positions, means for maintaining said switch normally in its off position, and means controllable from a distance and acting upon said maintaining means to shift the position to which said switch is returned by said maintaining means when manually released.
16. In combination, a manually-operated switch having a plurality of operative positions, means for maintaining said switch normally in its off position, and means controllable from a distance and acting upon said maintaining means to shift said switch to an operative position.
17. In combination, a manually-operated switch having a plurality of operative positions, means for maintaining said switch normally in its off position, an electromagnet acting upon said maintaining means to shift said switch to an operative position, and a switch at a distant station controlling the circuit of said electromagnet.
18. In combination, a switch, an operating handle therefor, yielding means for maintaining said switch normally in its off position, and a distant control system comprising means for shifting the point to which the switch tends to return when the operating handle is released.
19. In combination, a switch, an operating handle therefor, yielding means for maintaining said switch normally in its off position, and a distant control system comprising electrically-operated means for shifting the point to which the switch tends to return when the operating handle is released.
20. In combination, a switch, an operating handle therefor, yielding means for maintaining said switch normally in its off position, a distant control system comprising electromagnetically-actuated means for shifting the point to which the switch tends to return when the operating handle is released, and a switch at a distant point for controlling the circuit of said electromagnet.

In witness whereof I have hereunto set my hand this 17th day of May, 1904.

ARTHUR A. BUCK.
